Attorney.*

UNITED STATES PATENT OFFICE.

GEORGE W. GRIMM, OF WEST HOBOKEN, NEW JERSEY.

ARTIFICIAL TOOTH.

1,270,942.

Specification of Letters Patent.

Patented July 2, 1918.

Application filed November 13, 1917. Serial No. 201,752.

To all whom it may concern:

Be it known that I, GEORGE W. GRIMM, a citizen of the United States, residing at West Hoboken, in the county of Hudson and State of New Jersey, have invented certain new and useful Improvements in Artificial Teeth, of which the following is a full, clear, and exact specification.

This invention relates to artificial teeth, and has for its object to provide an improved porcelain crown tooth with an adjustable attachment for use on vulcanite plate work or other dentures.

Other objects are to provide an improved means of attachment of the teeth to the plate which permits said plate to be made lighter in weight and less bulky, to give greater comfort to the wearer, to afford more room for the tongue, to promote clearer enunciation by wearers of artificial teeth, to dispense with the use of vulcanite or other backing behind the porcelain crown, thereby improving the color or appearance of the tooth and making it more nearly like a natural tooth, and to permit the tooth to be ground away at the neck portion to fit the gum and conform to the alveolar ridge without weakening the attachment of the tooth to the plate or other denture.

A further important object is to make the attachment in separable parts so that the grinding and fitting to the alveolar ridge may be done before the final attachment is made. Other objects will appear as the description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:

Figure 1 is a vertical central section through a porcelain crown constructed in accordance with this invention, showing the first step in attaching it to a plate or denture.

Fig. 2 is a similar view showing the second step in making the attachment.

Fig. 3 is a section of the tooth or crown

completely attached to the plate or denture, and

Fig. 4 is a section on the line IV—IV of Fig. 3.

The porcelain crown or body portion of the artificial tooth 1 is formed with a cavity 2 in its end for connection with the vulcanite plate or other denture 12, as illustrated in Fig. 3. In order to strengthen this connection and form a dove-tailed or ball-and-socket joint, the socket or cavity 2 has an inwardly protruding ridge 3 intermediate its base and upper edge, and the walls of the cavity above and below said ridge are concave, as at 5 and 4. The diameter at the innermost edge of the ridge 3 is less than the greatest diameter of the concave portion 4 below said ridge.

To further strengthen the joint, a two part attaching device is employed, said device comprising an externally screw threaded pin 7 and a headed internally threaded part 8 to fit said pin. The crown 1 is bored at the bottom of the cavity 2 to receive the shank of the headed part 8, as at 6, and the pin 7 is anchored in the crown at the bottom of said bore and extends up centrally thereof to a point above the base of the cavity 2. The head 9 of said headed part is preferably provided with notches 10 to receive a spanner wrench, for adjusting same and also to prevent the sleeve 8 from becoming unscrewed or loose, after the vulcanite has set around same, as shown in Fig. 3. The lower face of the head is rounded or inclined, as at 11, to permit the vulcanite to flow or reach below said head and thus strengthen the connection.

As illustrated in Fig. 1, the first step in attaching the crown 1 to the vulcanite plate or denture 12 is the anchoring of the pin 7 in the bore 6 which is preferably done when the said crown is baked. While in this stage the crown may be ground to fit the gum and uneven surfaces of the alveolar ridge, this grinding being possible on account of the absence of the headed tubular part 8 which, if in position, as shown in Figs. 2 and 3, would be in the way of the grinding disk or tool generally used for grinding down and fitting the crown. If considerable grinding has been necessary, the lower end of the tubular part 8 may be ground off also so that

when it is screwed down the lower inclined or rounded face 11 of the head 10 will seat on the edge of the bore 6 in the bottom of the cavity 2. This feature not only strengthens the attachment but also permits in a manner never before possible the grinding or fitting of a tooth of this type at the part nearest the gum, so that such teeth can be used in spaces never before possible.

10. After the tooth or crown has been properly fitted, the headed tubular part 8 is screwed onto the pin 7, as already described and as illustrated in Fig. 2, a spanner or other wrench being used for this purpose 15 as previously suggested. The vulcanite is finally poured into the cavity 2 in plastic condition and after filling said cavity around and below the head 9 of the tubular part and above and below the ridge 3, said vulcanite is allowed to harden, whereupon the crown will be strongly fastened to the plate or denture formed of the vulcanite.

20. The top of the headed member or part is arranged below the ridge 3 in the cavity 2, so that the plastic material or vulcanite which fills the portion of the cavity below said ridge is held firmly around the head 9 of said member.

Having thus described my invention, what 30 I claim as new and desire to secure by Letters Patent of the United States is:

1. In an artificial tooth, the combination, with a crown having a cavity therein, of a pin anchored in the bottom of said cavity,

and a headed member connected to said pin 35 and adapted to be embedded in plastic material to which the crown is to be attached.

2. In an artificial tooth, the combination, with a crown having a cavity therein, of a pin anchored in the bottom of said cavity, 40 and a headed member connected to said pin and having an inclined under face, said headed member being adapted to be embedded in plastic material to which the crown is to be attached.

45. 3. In an artificial tooth, the combination, with a crown having a cavity therein provided with an inwardly extending ridge, of a pin anchored in the bottom of said cavity, and a headed member connected to said pin 50 and arranged between the bottom of the cavity and said ridge, said headed member being adapted to be embedded in plastic material to which the crown is to be attached.

4. In an artificial tooth, the combination, 55 with a crown having a cavity therein and a bore in the base of the cavity, of a screw-threaded pin anchored in the bottom of the bore and extending into the cavity, and an internally threaded tubular member to fit 60 said pin, said tubular member having a shank to loosely fit in said bore and a head extending into the cavity where it may be embedded in plastic material to which the crown is to be attached.

65. In testimony whereof I have signed my name to this specification.

GEORGE W. GRIMM.
